DISPLAY RACK

Julius Kroman, Minneapolis, Minn.

Application October 15, 1938, Serial No. 235,197

5 Claims. (Cl. 211—72)

My invention relates to display racks and particularly to such racks which may be disassembled.

In displaying greeting cards and many other kinds of relatively small articles it is usually very desirable to support the articles by means of a suitable rack.

An object of my invention is to provide a rack for supporting and displaying small articles which may be disassembled for compacting the rack for purposes of storage and transportation.

Another object is to provide such a rack so constructed that the major portions of articles placed therein are exposed for viewing thereof by an observer facing the rack.

Yet another object is to provide such a rack arranged to support an advertising card or the like disposed thereabove.

Still another object is to provide such a rack which may be quickly and easily assembled or disassembled, which is particularly rigid when in assembled condition, and which may be placed in very compact condition when disassembled.

A further object is to provide such a rack of light, simple and inexpensive construction.

These and other objects and advantages of the invention will more fully appear from the following description made in connection with the accompanying drawing, in which like reference characters refer to the same or similar parts throughout the views, and, in which:

Fig. 1 is a front view of an embodiment of my invention while the same is in assembled condition;

Fig. 2 is a partially broken-away, partial sectional end view;

Fig. 3 is a view of one of the parts of the rack of Figs. 1 and 2;

Fig. 4 is a view of another of the parts of the rack of Figs. 1 and 2; and

Fig. 5 is a view of still another of the parts of the rack of Figs. 1 and 2.

Referring to the drawing my display rack includes a pair of end panels 6 which when the rack is in assembled condition are aligned with each other and disposed in spaced parallel vertical planes. Each of the end panels 6 has a forward edge which slopes downwardly and forwardly in the major portion 6a thereof and is substantially vertically disposed in the lowermost portion 6b thereof. Each panel 6 in its upper rearward corner portion has a relatively short horizontally extending edge 6c.

A plurality of article supporting members 7 are disposed within the space between the respective end panels 6. The members 7 are arranged in a series thereof extending parallel to the sloping edges 6a of the panels 6. The members 7 are disposed parallel to each other and each one

thereof extends from one to the other of the panels 6 when the rack is in assembled condition.

Means is provided for removably connecting the upper portion of each article supporting member 7 to the panels 6. For this purpose ears 7a are provided at the upper ends of the respective end edges of each of the members 7 and are disposed in outwardly projecting relation thereto. The panels 6 are provided in the sloping forward marginal portions thereof with notches 6d for receiving the inner portions of the ears 7a on the members 7. The notches 6d as shown in Fig. 4 are inclined downwardly and somewhat forwardly so that the upper portions of the article supporting members 7 are accordingly inclined. The ears 7a as shown in Fig. 3 are widened in their free end portions to restrain the ears 7a from undesired horizontal movement in the notches 6d. Each member 7 is bent or folded along the dotted line 7b of Fig. 3 so that the lowermost portion 7c of each member 7 extends substantially forwardly.

Means is provided whereby the forwardly extending lower portion 7c of each member 7 is supported from the upper portion of the respective member 7 therebelow. The forwardly projecting portions 7c of the members 7 are each provided with forwardly projecting tongues 7d which are received in slots 7e formed in the upper portions of the members 7 as shown in Fig. 3. The rectangular member 8 shown in Fig. 5 is provided and extends across the lower front portion of the rack with its respective ends situated approximately at the vertically disposed lower edge portions 6b of the respective end panels 6. Means is provided for removably connecting the respective ends of the rectangular member 8 with the vertical edge portions 6b of the respective panels 6. Each panel 6 is provided with an ear 6e extending forwardly from the medial portion of the vertical edge 6b. Each ear 6e is extended upwardly in its outer portion to form a retaining element 6f. The respective ends of the member 8 are provided with ears 8a carrying depending retaining elements 8b. The member 8 is moved downwardly to its normal position during the process of assembling the rack so that the ears 6e and 8b are interengaged, as indicated in Fig. 2. The upper portion of the member 8 is provided with slots 8c similar to the slots 7e of the members 7 so that the tongues 7d of the lowermost one of the members 7 may be received in the slots 8c of the member 8.

The slots 7e of the uppermost one of the members 7 is not necessary but would be provided in practice due to the fact that one die or the like would be used in the manufacture of all of the members 7.

The uppermost portion of each of the panels 6 is provided with a notch 6g as shown in Fig. 60

4 by means of which a card 9 may be supported at its lower marginal portion in the notched uppermost portions of the respective panels 6 in the manner indicated in Figs. 1 and 2.

5 All of the above described parts of my rack may be constructed of suitable sheet material such as, for example, heavy cardboard. Obviously sheet metal could be used if desired.

In assembling the rack the panels 6 are placed 10 in aligned parallel properly spaced relation with each other whereupon the rectangular member 8 may be moved downwardly into interengaged relation with the ears 6e. The tongues 1d of the first member 1 above the member 8 may then be placed in the slots 8c of the member 8 where- 15 after the ears 8a of this first member 1 are thrust downwardly into the lowermost pair of notches 6d. The succeeding ones of the mem- 20 bers 1 may be successively placed in normal posi- 25 tion in a similar manner. The method of dis- assembling the rack is merely the reverse of the above described assembling process. The various parts of the rack when the rack is in disassembled condition may be placed together in a very compact group which is easy to wrap, transport, or store.

In Fig. 2 articles 10, which may be greeting cards or the like, are shown in dotted lines as having been placed in supported relation with the 30 uppermost one of the article supporting members 1. It is to be noted that the major portion of the frontmost one of the articles 10 is exposed to view from a point forwardly of the rack.

It is apparent that I have invented a novel, 35 light, compact and inexpensive type of display rack which is particularly capable of being rapidly and easily assembled and disassembled and which is relatively rigid when assembled and capable of being efficiently compacted when disassembled.

40 It will, of course, be understood that various changes may be made in the form, details, arrangement and proportions of the various parts without departing from the scope of my invention.

45 What is claimed is:

1. A disassemblable display rack comprising, a pair of similar aligned panels normally situated in respective spaced, parallel, vertical planes and each having a sloping forward edge, a series of generally rectangular article-supporting members arranged parallel to each other in a series extending parallel to said forward edges, each of said members normally extending from one to the other of said panels and being bent to be disposed other than horizontally in its upper portion and to extend generally forwardly in its lower portion, supporting elements projecting outwardly from the respective end edges of each of said members, said panels supportingly receiving said elements, and supporting elements projecting forwardly from the forward edge of each of said members, each of said members adjoined by another one of said members thereabove in its upper portion supportingly receiving the forwardly projecting supporting elements of said other one 65 of said members.

2. A disassemblable display rack comprising, a pair of similar aligned panels normally situated in respective spaced, parallel, vertical planes and each having a sloping forward edge, a series of substantially rectangular article-supporting members arranged parallel to each other in a series extending parallel to said forward edges, each of said members normally extending from one 70 to the other of said panels and being bent to slope

downwardly and somewhat forwardly in its upper portion and extend substantially forwardly in its lower portion ears projecting outwardly from the uppermost portions of the respective end edges of each of said members, said panels being provided in the forward marginal portions thereof with notches for receiving said ears, and tongues projecting forwardly from the forward edge of each of said members, each of said members adjoined by one of said members at a level 10 thereabove being slotted in its upper portion to receive the tongues of said other member.

3. The structure defined in claim 2 and said first-mentioned ears being shaped to protrude downwardly in their respective free end portions 15 to restrain said ears from undesired withdrawal from the notched portions of said panels.

4. A disassemblable display rack comprising, a pair of similar aligned panels normally situated in respective spaced, parallel, vertical planes, each 20 of said panels having a forward edge which slopes forwardly and downwardly in its major portion and is substantially vertically disposed in its lowermost portion, a series of generally rec- 25 tangular article-supporting members arranged parallel to each other in a series extending parallel to the sloping portions of said forward edges, each of said members normally extending from one to the other of said panels and being bent to be disposed other than horizontally in its upper portion and to extend generally forwardly in its lower portion, supporting elements projecting outwardly from the respective end edges of each of said members, said panels being arranged for supportingly receiving said elements, a flat mem- 30 ber extending between said lowermost portions of the forward edges of said respective panels, means for removably connecting the ends of said flat member to said respective forward edges, and supporting elements projecting forwardly from the forward edge of each of said first-mentioned members, said flat member and at least all of said first-mentioned members except the uppermost one thereof in its upper portion support- 35 ingly receiving the forwardly projecting supporting elements of the one of said first-mentioned members disposed next thereabove.

5. A disassemblable display rack comprising, a pair of similar aligned panels normally situated in respective spaced, parallel, vertical planes, each 40 of said panels having a forward edge which slopes forwardly and downwardly in its major portion and is substantially vertically disposed in its low- 45 ermost portion, a series of generally rectangular article-supporting members arranged parallel to each other in a series extending parallel to the sloping portions of said forward edges, each of said members normally extending from one to the other of said panels and being bent to be disposed other than horizontally in its upper portion and to extend generally forwardly in its lower portion, means for removably connecting the upper portions of the respective end edges of each of said members to said panels, a flat mem- 50 ber extending between and removably connected to said lowermost portions of the forward edges of said panels, and tongues projecting forwardly from the forward edge of each of said first-men- 55 tioned members, said flat member and at least all of said first-mentioned members except the uppermost one thereof each having slots in the upper portion thereof receiving the tongues of the one of said first-mentioned members disposed next thereabove.
